(57) **CLAIM**

The ornamental design for a toy track piece set, as shown and described.

DESCRIPTION

FIG. 1 is a perspective view of the first toy track piece of the toy track piece set, shown separately for ease of illustration; FIG. 2 is another perspective view thereof; FIG. 3 is a front elevational view thereof; FIG. 4 is a rear elevational view thereof; FIG. 5 is a left side elevational view thereof; FIG. 6 is a right side elevational view thereof; FIG. 7 is a top plan view thereof; and FIG. 8 is a bottom plan view thereof;

FIG. 9 is a perspective view of the second toy track piece of the toy track piece set, shown separately for ease of illustration;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof; and,

FIG. 17 is a perspective view of the toy track piece set, shown with the second toy track piece attached to the first toy track piece for completeness of illustration.

The broken lines in the drawings depict portions of the toy track piece set that form no part of the claimed design.

1 Claim, 17 Drawing Sheets
